UNITED STATES PATENT OFFICE

2,525,640

NOZZLE

Gustave A. Borg, Naugatuck, Conn.

Application September 9, 1944, Serial No. 553,334

1 Claim. (Cl. 299—131)

1

The invention relates to nozzles and more particularly to nozzles designed for use with hose of the type exemplified by conventional garden hose.

The invention has for its object to provide a nozzle of the indicated class which is simple in construction and of maximum efficiency in operation.

Another object of the invention is to provide a novel nozzle having a minimum of parts and in which undesirable leakage is positively and efficiently avoided.

The invention contemplates further the provision of a nozzle which may be controlled and regulated without effort to provide issuing streams of water or its equivalent of varying characteristics and particularly streams in which the water is atomized and reduced to a fine mist.

A further object of the invention is to provide a novel nozzle in which the component parts are capable of being made of plastics to produce an efficient and easily operated arrangement.

Other objects will appear from the description hereinafter and the features of novelty will be pointed out in the claim.

In the accompanying drawing, which illustrates examples of the invention without defining its limits,

Fig. 1 is a central longitudinal section of the novel nozzle in one form;

Fig. 2 is a cross-section on the line 2—2 of Fig. 1;

Fig. 3 is a central longitudinal section of the controlling and regulating cap of the nozzle, and

Fig. 4 is a central longitudinal section of the novel nozzle in another form.

The nozzle comprises a tubular body preferably of cylindrical form and consisting of a cylindrical section 5 having an externally-threaded section 6 at its one end, and a continuing preferably cylindrical section 7 projecting from said threaded section 6 in axial registry with the section 5.

A converging, preferably conical head 8 projects from the section 7 in an axial direction and at its base is of less exterior diameter than the section 7 so as to form an annular shoulder 9 at this point. The outer surface of the conical head 8 is perfectly smooth and even for the purpose to be more fully set forth hereinafter. A preferably cylindrical stem 10 extends from the conical head 8 in axial outward direction and terminates in a boss 11 having an annular lower edge which preferably is beveled as shown at 12; as shown, the upper surface of the boss 11 may converge towards the center to form a conical apex.

As shown, the tubular body includes an axial channel or bore consisting of a section 13 and a continuing section 14 of reduced diameter to form an internal annular shoulder 15 at the point of connection of the two channel sections as illustrated in Fig. 1. The channel section 14 terminates in and communicates with diverging outlet

2

channels 16 located in the conical head 8 and having their exit ends located at the outer surface thereof. In the preferred arrangement the outlet channels 16 themselves each diverge toward their exit ends, with the upper surface portions 17 of said channels 16 extending at steeper angles than the lower surface portions thereof, and forming an interior relatively sharp point or apex 18 in registry with the channel section 14. At a suitable intermediate point the body section is preferably provided with an annular surface groove for accommodating a packing gasket 19 secured in place in any convenient manner.

In addition to the parts so far described, the nozzle includes means for controlling the flow of water therethrough and for regulating the type and character of the outflowing stream.

In the illustrated example the controlling means comprises a cap 20 mounted in threaded engagement with the section 6 of the body section 5 for rotatable adjustment thereon. As shown in Figure 1, the threaded portion of the cap is of greater axial extent than the section 6, extending beyond both ends of the section 6 when the cap is fully closed. The cap 20 includes an internal cylindrical section having a straight, even surface 21, and dimensioned to rotatably fit upon the body section 7. In addition, said cap 20 is provided internally with a converging or conical surface 22 dimensioned and arranged to snugly fit the outer surface of the conical head 8, when said cap 20 is in its closed position. At its base, the converging or conical surface 22 terminates at an internal annular transverse shoulder 23 extending between the surfaces 21 and 22, as shown in Figs. 1 and 3. A preferably cylindrical surface extends axially outward from the conical surface 22 to constitute an axial passage 24 terminating in a flaring exit end 25 opening in the outer end face of the cap as illustrated in Figs. 1 and 3. The diameter of the passage 24 is such as to loosely accommodate the boss 11 and stem 10 as shown in Fig. 1.

In the fully closed position of the nozzle, the cap 20 is screwed down upon the section 6 until the surface 22 is in firm surface engagement with the outer surface of the conical head 8 which projects into the cap passage 24. At this stage, the exit ends of the outlet channels 16 are covered by the cap 20 and sealed by the engagement of the cap surface 22 with the surface of the conical head 8. Both of these surfaces are smooth and contact with each other throughout to provide a watertight closure and seal whereby the nozzle is efficiently closed against the exit of water or its equivalent therethrough. Leakage is prevented by the single gasket 19 which is in sealing engagement with the cylindrical surface 21 of the cap 20. Complete closure of the nozzle is effected, however, by the surface 22 of the cap 20 in association with the surface of the conical head 8.

To open the nozzle, the cap 20 is rotated on the

threaded section 6 in a direction to shift said cap outwardly and thereby adjust the surface 22 out of contact with and away from the outer surface of the conical head 8.

This unseals the exit ends of the outlet channels 16 and enables water to pass therethrough from the axial channel 13, 14. As the water passes through the outlet channels 16 it is diverted thereby and particularly by the surface portions 17 and apex 18 thereof in the form of diverging streams, in opposite directions against the conical surface 22 of the cap and along the latter in a converging stream toward the axial passage 24. The water, in a confined stream, passes along the conical surface 22 and through said axial passage 24 into contact with the beveled annular lower edge 12 of the boss 11. The stream of water will accordingly be divided into a mist or atomized and spread to an extent dependent upon the location of the flaring exit end 25 of the passage 24 relatively to the boss 11. This relationship will determine the spread of the water passing out through the nozzle as will be apparent. If the adjustment of the cap 20 is such as to bring the exit end 25 of the passage 24 outwardly beyond the boss 11, the water will flow from the nozzle in a substantially solid stream spread only to a degree determined by the flare of said exit end 25. At all of these stages, the packing gasket 19 prevents undesirable leakage back through the cap 20.

The nozzle is provided with coupling means for connecting the same with a hose, which means may be of any suitable type or which may comprise the novel device shown and forming the subject-matter of another application filed by me.

The illustrated coupling means includes a hollow body 26 having a surface opening 28 and provided interiorly with axially spaced bearing surfaces 29 and 30 for developing an axial clamping action on heads 31 and 32 respectively. The latter form part of a stem 33 secured in the end of a hose 34 by means of a sleeve 35 and associated elements.

The form of the novel nozzle shown in Fig. 4 corresponds in construction and operation with the nozzle illustrated in Fig. 1, and differs therefrom only in the type of coupling means whereby the nozzle is connected with a hose.

In the form now being described, the body section 5 is provided at its free end with an externally-threaded upset portion 36 for the threaded accommodation of an internally-threaded sleeve 37. A stem 38 projects axially from the boss 36 and terminates in a preferably frusto-spherical head 39, it being understood that an axial passage 40 extends through the head 39, stem 38 and boss 36 into communication with the channel section 13 of the nozzle.

This coupling means is connected with the hose 41 by forcing the head 39 and stem 38 into the end thereof until the end face of said hose engages the face of the boss 36. The sleeve 37 is then adjusted into contact with the outwardly bulged portion of the hose 41 to co-operate with the head 39 and stem 38 in fixing the nozzle securely in connection therewith.

The nozzle, in all of its novel forms, is easily operated with a minimum of effort to control the water at will and to vary the character of the outflowing stream in a manner to provide the most efficient results dependent upon the use to which the associated hose is put.

The novel nozzle is specially adapted for use with garden hose for watering purposes, and may

be constructed of any suitable material. The novel nozzle is specially adapted to be made of suitable plastics and avoids the necessity for complicated packing to prevent leakage.

Although the present invention has been described in conjunction with preferred embodiments, it is to be understood that modifications and variations may be resorted to without departing from the spirit of the invention, as those skilled in the art will readily understand. Such variations and modifications are considered to be within the purview and scope of the claim.

I claim:

A hose nozzle entirely of plastic material comprising a hollow cylindrical body having an inlet end and an exit end, an internal channel located axially within said hollow cylindrical body and connecting said inlet end with said exit end, a conical head integral with said body at the exit end, an annular shoulder at the base of said conical head, diverging outlet channels incorporated within said head and in communication with the internal channel, a small stem projecting axially from said head, a boss on the tip of said stem, an externally threaded section on the outer surface of said hollow body and spaced from said annular shoulder; a cap mounted on the exit end of said hollow body and consisting of a hollow cylindrical shell, an internally threaded portion having threads of greater axial extent than said externally threaded section on the hollow body and located near one end of the shell for cooperation with said externally threaded section on said hollow body, an even internal surface at an intermediate portion of said cap and rotatably and closely fitting a smooth section of said hollow body, a conical internal surface on said cap adapted to fit upon and cooperate with said conical head, a flaring exit end on the cap and having a passage loosely accommodating the stem and the boss of said hollow body to permit the passage of a stream of water therebetween, and said conical head projecting into the cap exit end passage to close the same when the cap is screwed inwardly on the hollow body, and said cap having an annular shoulder at the base of its conical internal surface for contact against said annular shoulder at the base of the conical head on the hollow body to define the close position for the nozzle and to prevent further inward travel of the cap beyond its closed position.
